UNITED STATES PATENT OFFICE

2,489,389

AWNING

Christian E. Skyum, Chicago, Ill.

Application October 22, 1945, Serial No. 623,639½

5 Claims. (Cl. 160—390)

1

The invention relates to awnings.

One object of the invention is to provide an awning curtain which is adapted to be connected to a pivoted frame with improved devices for detachably connecting one end of the curtain thereto.

Another object of the invention is to provide an improved device for detachably connecting one end of a fabric curtain to the frame, which includes a metallic strip or bar through which uniform tension is applied to the fabric of the curtain for preventing localized wear.

Other objects of the invention will appear from the detail description.

The invention consists in the several novel features which are hereinafter set forth and are more particularly defined by claims at the conclusion hereof.

In the drawings:

Fig. 1 is a side elevation, of an awning embodying the invention, the connecting bar of swinging frame being shown in section.

Fig. 2 is a sectional perspective illustrating the devices for detachably connecting the lower or outer end of the awning curtain to the pivoted bail or frame.

Fig. 3 is a perspective of the metallic strip which is removably held in a loop of the awning curtain and used for connecting the curtain to the pivoted frame.

Fig. 4 is a section taken through one of the cross-hooks for connecting the curtain to the cross-member of the bail.

The invention is exemplified with an awning 7 which has one of its ends connected to a roller 8 which is rotatably mounted in brackets 9, which are secured to the outside of a window casing or wall 10. This roller is adapted to wind and unwind the curtain for raising and lowering its lower end. The lower end of the curtain is connected, as hereinafter described, to a bail or frame, which comprises side-arms 11 having their inner ends pivoted to brackets 12, which are fixed to the outer face of the casing or wall 10, and a cross-bar or member 13 which rigidly connects the outer ends of arms 11. Any suitable means, as well understood in the art, may be used for rotating the roller 8 for winding and unwinding the curtain 7.

The curtain 7 is usually detachably connected to the roller 8, in any suitable manner. The lower or outer end of the curtain is formed on its underside with a loop 14 which extends transversely across the curtain. The loop 14 is formed by a seam 15 from which the outer fold 18 is extended

5 to lap over the bar 13 of the swinging frame. A strip 16 of metal, which is U-shaped in cross-section, fits into and is adapted to be supported by the lower end of the loop 14 of the curtain. One flange 19 of strip 16 fits the inner face of the lower member of loop 14 and the other flange 20 fits against the inner face of the upper member of loop 14. Flange 20 of strip 16 is provided in its upper edge with a series of notches 22. The 10 upper member of loop 14 is provided with a series of slits or holes 21 in registry with the notches 22 in flange 20 of strip 16. A series of clips 24 formed of flat strips of metal are provided with hooks 25 which are adapted to pass through slits 21 and notches 22 in flange 20 of strip 16 and their inner terminals fit against the bottom of strip 16 between flanges 19 and 20. The lower end of each clip 24 is also bent to form a lower hook 26 which is adapted to embrace the cross-bar 13 of the pivoted frame.

In attaching the lower end of the curtain to the bail or pivoted frame, the strip 16 is first inserted into the open ended loop 14 of the curtain with the notches 22 in registry with the slits 21. 15 The outer fold 18 of the curtain 7 can be folded upwardly so that the slits will be visible. The hooks 25 of clips 24 are then passed through slits 21 and notches 22 so that clips 24 will be supported by the strip 16. Next, the hooks 25 are 20 snapped around the cross-bar 13. The lower end of the curtain will then be attached to the swinging frame, and fold 18 will be lowered to conceal the slits 21 and clips 24.

When it is desired to detach the curtain from the frame, clips 24 are disconnected from cross-bar 13 and hooks 25 are withdrawn from strips 16 and slits 21. Strip 16 can then be withdrawn endwise from loop 14 of the curtain.

The invention exemplifies simple devices for 25 detachably connecting one end of the curtain to the swinging frame. The clips for securing one end of the curtain to the swinging frame are simple in construction and can be formed of flat metal at a very low cost.

30 The invention is not to be understood as restricted to the details set forth, since these may be modified within the scope of the appended claims, without departing from the spirit and scope of the invention.

Having thus described the invention, what I claim as new and desire to secure by Letters Patent is:

35 1. The combination with a curtain, provided with a loop extending transversely thereacross and an extension overlying the loop, and a sup-

2

port for one end of the curtain including a member underlying said extension, of a metallic strip removably held in said loop, and clips underlying the extension extending through one fold of the loop, detachably secured to the strip, and connected to the support.

2. The combination with a curtain, provided with a loop extending transversely thereacross and an extension overlying the loop and a support for one end of the curtain including a member underlying said extension, of a metallic strip U-shaped in cross-section and extending substantially from end to end of and endwise insertable into and removable from said loop, and clips underlying the extension extending through one fold of the loop, detachably connected to the strip, and connected to the support.

3. The combination with a curtain provided with a loop extending transversely thereacross and a support for one end of the curtain, of a metallic strip U-shaped in cross-section and extending substantially from end to end of and endwise insertable into and removable from said loop, and clips extending through one fold of the loop, detachably connected to the strip, and connected to the support, one flange of the strip being provided with notches through which the clips extend.

4. The combination with a curtain provided with a loop extending transversely thereacross and an extension overlying the loop and a pivoted frame for supporting one end of the curtain

including a member underlying said extension, of a metallic strip U-shaped in cross-section and extending substantially from end to end of and endwise insertable into and removable from said loop, and clips underlying the extension extending through one fold of the loop, provided with hooks engaging the strip and connected to the frame.

5. The combination with a curtain provided with a loop extending transversely thereacross and an extension overlying the loop and a pivoted frame for supporting one end of the curtain including a member underlying said extension, of a metallic strip U-shaped in cross-section and extending substantially from end to end of and endwise insertable into and removable from said loop, and clips underlying the extension provided with hooks extending through one fold of the loop and engaging the strip, and with hooks removably connected to the frame.
